(57) **CLAIM**

The ornamental design for an electronic device with a modular tablet stand, as shown and described.

DESCRIPTION

FIG. 1 is a perspective view of an electronic device with a modular tablet stand.

FIG. 2 is a back view of the electronic device with a modular tablet stand of FIG. 1; and,

FIG. 3 is a left side view of the electronic device with a modular tablet stand of FIG. 1.

The broken lines of the FIGURES are for illustration only. The broken lines of the preceding FIGURES illustrate boundaries and, therefore, the broken lines and the unshaded regions bounded by broken lines of the preceding FIGURES form no part of the claimed design. Line shading is not surface ornamentation.
